UNITED STATES PATENT OFFICE.

ROBERT O. YOUNG, OF PITTSBURG, PENNSYLVANIA, ASSIGNOR OF THREE-FIFTHS TO THE MASSILLON STONE AND FIRE BRICK COMPANY, OF SAME PLACE.

TUyERE.

SPECIFICATION forming part of Letters Patent No. 393,136, dated November 20, 1883.

Application filed May 2, 1887. Serial No. 236,751. (No model.)

To all whom it may concern:

Be it known that I, ROBERT O. YOUNG, of Pittsburgh, in the county of Allegheny and State of Pennsylvania, have invented a new and useful Improvement in Tuyeres; and I do hereby declare the following to be a full, clear, and exact description thereof.

My invention relates to an improvement in tuyeres for use in cupola-furnaces, and is illustrated in the accompanying drawings, in which—

Figure 1 is a horizontal section through the wall of a cupola-furnace, showing the tuyeres, the section being on the line *y y* of Fig. 2. Fig. 15 2 is a vertical cross-section on the line *x x* of Fig. 1. Fig. 3 is a perspective view of one of the parts of the tuyere.

Like symbols of reference indicate like parts in each.

20 In the drawings, Figs. 1 and 2, 2 represents the wall of the furnace, 3 is the jacket which incloses the wall, and 4 is the wind-box. The tuyeres are made of fire brick or clay, and consist of several parts, as shown in the drawings.

25 The inner sections, 5, are flat tiles, whose edges are inclined so as to conform with the radial lines of the furnace. The faces of the sections 5 are grooved, and, when superposed, the grooves form the hollow bore or passage of the 30 tuyere. At the back of the sections 5 are other sections, 6, which are similarly superposed and grooved, and whose bore forms a continuation of the bore of the sections 5 in the same lines therewith. In order to break joint with the 35 tile-sections 5, the sections 6 are made of less width, and other tile, 7, are built in the wall to fill up the spaces. The tiles 5 and 6 together form the tuyere, which at the front end opens into the furnace and at the rear is 40 in communication with the wind-box.

My reason for making the tuyere in four sections is that the inner sections, 5, being more directly exposed to the heat of the furnace, burn out more rapidly than do the outer sections, 6, 45 and may be removed from time to time without need of renewing the outer sections. In this way I get a distinct saving in the cost of the tuyere.

As shown in Figs. 1 and 3, the grooves in the faces of the tiles are made at such an inclination that the bore of the tuyere shall be flared inwardly—that is, it shall be wider at the inner end than at the rear or wind-box end—and shall gradually taper from one end to the other.

Tuyeres of cupola-furnaces are apt to become 55 clogged with molten metal from the interior of the furnace, and when that happens with the tuyeres heretofore in common use it is necessary to drop the bottom of the cupola, remove the fuel and charge, and, after cooling the furnace, the 60 choked tuyere is torn out and another tuyere substituted. Besides the loss of metal occasioned by this operation it causes a loss of time and an outlay of considerable labor and money. All this is avoided by the use of the 65 inwardly-flaring brick tuyere, because the clogging metal can be forced out by a tool inserted into the tuyere from the outside, and on account of the easily-frangible nature of the brick the adhering metal will chip off on the 70 inside, so as to allow the easy discharge of the metal without damaging the body of the tuyere, as it would were it made of metal.

I claim—

1. As a new article of manufacture, a hollow 75 inwardly-flaring brick tuyere for melting-furnaces, substantially as and for the purposes described.

2. As a new article of manufacture, a hollow 80 inwardly-flaring brick tuyere for melting-furnaces, said tuyere being made of longitudinally-divided sections, substantially as and for the purposes described.

3. The combination, with a melting-furnace, of a sectional tuyere composed of the inwardly-concave bricks 5 5, set in the furnace-wall, one above the other, and similar bricks, 6 6, set outside of the bricks 5 5, all of said bricks together constituting a continuous tuyere, substantially as and for the purposes described. 85 90

In testimony whereof I have hereunto set my hand this 14th day of April, A. D. 1887.

ROBERT O. YOUNG.
